REFRIGERATION

Alfred G. Gross, Chicago, Ill., assignor to The
Hoover Company, North Canton, Ohio, a cor-
poration of Ohio

Application February 3, 1938, Serial No. 188,412

17 Claims. (Cl. 62—108.5)

This invention relates to mechanical refrigerators and particularly to apparatus for making clear ice cubes.

The ice cubes formed in household mechanical refrigerators are not satisfactory because the ice is foggy in appearance due to the occluded gases, creating the impression that the ice cubes are unsanitary.

Accordingly, it is an object of my invention to provide apparatus for making clear ice cubes. Another object of my invention is to provide means for forcing refrigerated air through the contents of a refrigerator tray to remove the air or occluded gases from the contents, as the latter freezes. Another object of the invention is to provide means for interrupting the flow of air through the contents of the refrigerator tray after the contents are frozen. A further object is to provide apparatus cooperable with a compressor for forcing air through the contents of the refrigerator tray. Another object is to provide a pump in the refrigerator control circuit for forcing air through the contents of the tray. Another object is to provide apparatus responsive to the vibration of the refrigerator unit to force air through the contents of a tray. A further object is to provide a new and improved refrigerator tray. Other objects and advantages of the invention will be apparent from the specification and drawings, wherein:

Fig. 1 is a fragmentary sectional view of a refrigerator cabinet showing the arrangement therein of one embodiment of my invention for forcing air through the contents of an ice tray;

Fig. 2 is a fragmentary enlarged view of the apparatus for forcing air through the contents of an ice tray;

Fig. 3 illustrates another embodiment of the invention showing the compressor of the refrigerator unit adapted to be connected to the ice tray;

Fig. 4 illustrates still another embodiment of the invention wherein the vibration of the refrigerator unit is employed to force air through the contents of the ice tray; and

Fig. 5 is an enlarged sectional view of a diaphragm pump operated by the vibration of the refrigerator unit to force air through the contents of the ice tray.

The embodiment of the invention shown in Figures 1 and 2 comprises a refrigerator cabinet having a top wall 10, a door 11, a rear wall 12, and a cabinet flue 13. Suitably mounted in the cabinet is an evaporator 14 formed from coiled continuous tubing to provide a plurality of hori-

zontally spaced straight pipe portions 16, on which are mounted shelves 17 for the reception of refrigerator trays 18. The evaporator 14 is enclosed in a housing 19 having a top wall 20, side walls 21, a bottom wall 22, a rear wall 23, 5 and a door 24. Disposed beneath the evaporator is a drip pan 25.

The ice tray 18 comprises a pair of side walls 26, a rear wall 27 and a bottom wall 29. Welded or otherwise secured to the inner surface of the 10 bottom wall 29 is a plate 30 provided with a plurality of parallel raised corrugations 31 which extend substantially throughout the length of the ice tray 18 and cooperate with the bottom plate 29 to form passageways 32 for refrigerated air. 15 The inner plate 30 extends from the front end of the ice tray rearwardly to a point spaced from the rear wall 27 and then projects upwardly in spaced parallel relation with respect to the rear wall 27 to the upper defining edge thereof to 20 form a chamber 35 which communicates with all the passageways 32. Removably disposed in the ice tray 18 is a grid 36 to provide a plurality of ice cube chambers 37 for forming individual ice cubes. It will be noted that the corruga- 25 tions 31 are provided with a plurality of openings 38, each opening communicating with an ice cube chamber 37. Extending from the rear wall 27 of the ice tray is a hollow connecting element 40 which is tapered for engagement with 30 a complementary flared connecting element 41 mounted in the rear wall 23 of the evaporator housing. The connecting elements 40 and 41 are composed of insulating non-freezing material. In order to insure alignment between the 35 connecting elements 40 and 41, the side walls 21 of the evaporator housing 19 are provided with inwardly extending ribs 43 which position the ice tray 18 laterally between the side walls 21 of the evaporator housing. 40

Extending rearwardly from the connecting element 41 and through the back wall 12 of the cabinet is a conduit 45 connected to the outlet of a pump 46 provided with slidably vanes 47 in engagement with the wall of the cylinder, and 45 which are rotated by a motor disposed in a housing 48. As shown in Figure 1 the pump and motor are connected together as a unit and are mounted on the rear wall of the cabinet in the flue 13. The vanes 47 of the pump 46 suck refrigerated air through a tube 49 having its inlet 64 disposed in the refrigerator cabinet at the rear of the evaporator. In the operation of the pump or fan 46 refrigerated air is drawn from the refrigerator

- cabinet through the tube 49 and forced through the tube 45 into the chamber 35 from whence the air is distributed through the passageways 32 and discharged through the openings 38 into each ice cube chamber 37, the escaping refrigerated air agitating the water in the ice tray removing the occluded gases therein to provide clear ice cubes.

In order to control the flow of the refrigerated air through the ice tray I have provided a control mechanism comprising a thermostatic device including a bulb 50 disposed in the evaporator where it is responsive to the temperatures in the evaporator. This device includes a temperature responsive fluid which actuates a flexible bellows 51, to move a contact 52 into and out of engagement with a contact 53 to complete a circuit to the motor 48.

The wiring diagram for the control circuit comprises a conductor 55 leading from the relatively stationary contact 53 to a conductor 56 connected to the refrigerator unit, which may be an absorption system not shown, and also to a control box 57 mounted on top of the evaporator housing 19, a conductor 58 extends from the control box 57 to a source of current, and connected to the other contact 52 is a conductor 60 leading to the motor 48 from which a lead 61 extends to a conductor 62 connected to the refrigerator unit and the source of current. The refrigerator unit may be either of the absorption or compressor type.

In operation, assume that the ice tray 18 is filled with water and properly positioned on the evaporator shelf 17. The thermostatic bulb 50 reacts to the high temperature of the water in the ice tray and actuates the flexible bellows 51 to close the contacts 52 and 53 which closes the circuit to the motor 48 causing the pump 46 to rotate the vanes 47 which suck refrigerated air from the cabinet through the inlet 64 of the tube 49 and forces the refrigerated air through the conduit 45, thence through the connections 41 and 40 into the chamber 35 of the ice cube tray 18. Due to the pressure created by the vanes 47 of the pump 46 the refrigerated air is forced through the passageways 32 and discharged through the openings 38 into the ice cube chambers 37. The refrigerated air then passes upwardly through the water in the ice cube chambers 37 and causes the occluded gases or air bubbles to rise to the surface of the water and are discharged into the atmosphere, whereby ice cubes are formed that are clear in appearance. When the water has frozen, the thermostatic bulb 50 will operate to deflate the bellows 51 to thereby break the switch contacts 52 and 53 and interrupt the circuit to the motor 48. Accordingly the pump 46 will not operate to force air through the ice cubes after the water has frozen.

Another method of forcing refrigerated air through the water in the ice tray 18 is shown in Figure 3 and comprises a refrigerator cabinet 70 mounted on a base 71. A compressor type of refrigerator unit is mounted on a platform 73 which is resiliently supported by means of springs 74 suspended from brackets 72 disposed at the four corners of the cabinet. The refrigerator unit comprises a motor 75 which may be provided with a fan for cooling a condenser 76, a compressor 77 and a liquid receiver 78. The compressor includes a cylinder 79, piston 81 and crank case 80 having an inlet 83. A discharge check valve 85 is provided in the cylinder 79 and an intake valve 82 in the piston 81. On the

down stroke the piston travels against the pressure of gas in the crank case, and the piston valve 82 opens, permitting gas to flow above the piston 81, while on the up-stroke this valve closes and the gas is compressed and forced out through the check valve 85 into a conduit 86 to the condenser 76. The compressor is connected with an evaporator, for example the one shown in Figure 1, by means of a conduit 89 connected with the pipe 90 of the evaporator 14, and a conduit 91 extends from tube 92 of the evaporator 14 to the inlet 93 of the compressor crankcase.

In order to force air through the water in the ice tray 18 a flexible bellows 94 is secured exteriorly of the crank case 80 and communicates through an opening 96 with the interior of the crank case. A housing 95 is disposed in spaced relation about the flexible bellows 94 to form a chamber 97 and is provided with a check valve 98 to control the communication of the chamber 97 with the atmosphere, and another check valve 99 to control communication of the chamber 97 with a conduit 101. This conduit extends upwardly to the connecting element 41 of the evaporator housing 19 for communication with the passageways 32 in the ice tray 18. Disposed in the conduit 101 is a safety valve 102 to allow air to escape if the compressor operates after the water in the ice tray 18 has frozen.

In the operation of this embodiment, the compressor 77 is operated by the motor 75, the compressor forcing refrigerant such as sulphur dioxide through the conduit 86 to the condenser 76 wherein the refrigerant is condensed and passes through the conduit 87 into the liquid receiver 78. From the receiver 78 the refrigerant passes by means of the pipe 89 up to the pipe 90 of the evaporator 14 where it performs its refrigerating effect in the well known manner and the vaporized refrigerant then passes down through the pipe 91 into the compressor crankcase 80.

During the operation of the compressor 77 the pressure of the vapor refrigerant in the crankcase 80 is constantly changing and it is the purpose of my invention to utilize this constantly changing pressure to operate the flexible bellows 94 and force air into the ice tray 18. Since the pressure of the refrigerant vapor in the crank case 80 is constantly changing it will reciprocate the flexible bellows 94 and when the flexible bellows 94 is relatively deflated the valve 98 will open the port 100 whereby air will pass from the atmosphere into the chamber 97, and when the flexible bellows 94 is inflated it will open the valve 99 and force the air from the chamber 97 through the conduit 101 and thence through the connections 41 and 40 into the chamber 35 of the ice tray 18 as shown in Figure 2. Thereafter, the air is forced through the passageways 32 and discharged through the ports 38 into each ice cube chamber 37 to force the occluded gases out of the water and thereby produce clear ice. If the compressor 77 continues to operate after the ice is frozen, the pressure of the air in the conduit 101 will build up to such an extent to operate the safety valve 102 and release the pressure of the air in the pipe 101, so that the air does not pass into the ice cube chambers 37. The temperature of the flexible bellows 94 is relatively low due to the cold gases in the crankcase 80, and accordingly the air pumped into the ice tray will be relatively cold since the bellows contacts the air in the chamber 97 prior to pumping the air into the ice tray 18. If desired, the port 100 in the housing 95 may be connected by a con-

duit to the cabinet to supply refrigerated air to the chamber 97 and then to the ice tray 18.

Another embodiment of the invention is shown in Figures 4 and 5, and includes a refrigerator unit similar to that described in connection with Figure 3. In this modification I employ the vibration of the platform 73 caused, by the operation of the refrigerator unit, to operate a diaphragm to pump air through the ice cube tray 18.

Interposed between the platform 73 and the base 71 of the refrigerator cabinet is a diaphragm pump having a housing comprising lower and upper sections 105 and 106, respectively, secured together by means of rivets 107. Interposed between the housing sections 105 and 106 is a flexible diaphragm 108 forming with the housing, chambers 109 and 110. The chamber 109 is provided with a check valve 112 which controls communication to a pipe 113 extending upwardly through the cabinet and terminating interiorly of the cabinet adjacent the evaporator for conveying refrigerated air from the cabinet, the check valve 112 permitting the refrigerated air to pass from the refrigerator into the chamber 109. Another check valve 114 permits one-way communication from the chamber 109 through a conduit 115 which is adapted to be connected with the connections 41 and 40 for communication with the ice tray 18 shown in Figure 2. A safety valve 116 is interposed in the conduit 115 to permit the escape of air after the water is frozen in the ice tray. Connected to the diaphragm 108 is a vertically extending rod 117 disposed in a sleeve bearing 118 carried by the upper casing 106, and the rod 117 is provided at its upper end with a cup shaped container 119 for the reception of the ball 120 which rotatably engages the platform 73. Disposed about the rod 117 and interposed between the cup 119 and the bearing 118 is a spring 121 which at all times urges the ball 120 into engagement with the platform 73.

In the operation of this embodiment assume that the ice tray is filled with water and the refrigerator unit is operating. Operation of the refrigerator unit causes the platform 73 to vibrate and due to the springs 14 this vibration is transmitted to the loose joint comprising the ball 120 and rod 117 to the diaphragm 108, with the result that the diaphragm 108 is vibrated. Upon the upstroke of the diaphragm 108 refrigerated air will be drawn through the conduit 113 from the cabinet into the chamber 109. Upon the downward stroke of the diaphragm the refrigerated air is forced from the chamber 109 through the conduit 115 into the chamber 35 of the ice tray 18, and thence through the passageways 32 and is discharged through the openings 38 into the ice cube chambers 31. Thus the occluded gases are forced out of the water while the latter is freezing to provide clear ice. If the refrigerator unit continues operating after the water is frozen, the air that is being forced through the conduit 115 escapes through the safety valve 116.

Although I have described my invention in connection with an ice cube tray, it is obvious that it is not necessary to only freeze water in the tray but my invention may be employed in connection with any liquid or food that should be aerated during the preparation of the same. Other means than those disclosed may be employed for forcing fluid through the contents of the tray. In the foregoing embodiments I have shown but one ice tray of the clear ice type, but if desired additional clear ice trays may be connected to the clear ice making system to agitate

the contents of the tray. The contents of the ice tray may be agitated by a relatively large volume of air at low pressure, or a relatively small volume of air at high pressure, by adjusting the size of the discharge openings in the clear ice trays, the size of the passageways in the clear ice systems and the pressures obtained by the devices producing the air pressure in the system. It will be noted that the air discharged into the clear ice tray is refrigerated, in fact, it is refrigerated prior to initially entering the system adjacent the evaporator. Accordingly, the refrigerated air is dry prior to entering the system and will not condense in the system and adhere to the tubes to obstruct the flow of air in the latter, however, air other than refrigerated air may be employed in the system.

While I have illustrated and described several embodiments of my invention, it is to be understood that these embodiments are to be taken as illustrative only and not in a limiting sense. I do not wish to be limited to the structures shown but to include all equivalent variations thereof except as limited by the scope of the appended claims.

I claim:

1. In a refrigerator, a cooling unit, an ice tray removably disposed in heat transfer relationship with said cooling unit, means in said tray providing a passageway for fluid to the contents of said tray, and pumping means communicating with said passageway and with the interior of said refrigerator, said pumping means operating to remove refrigerated air from said refrigerator and to force the same through said passageway into the contents of said tray to remove occluded gases from water being frozen therein.

2. In a refrigerator, a tray removably disposed in said refrigerator, a refrigerator compressor, means responsive to the changes in pressure in the crankcase of said compressor for forcing fluid into the contents of said tray to agitate said contents.

3. In a refrigerator, a tray removably disposed in said refrigerator, means in said tray providing a passageway for fluid to the contents of said tray, a refrigerator compressor, and means responsive to the changes in pressure in the crankcase of said compressor for forcing fluid through said passageway into the contents of said tray.

4. In a refrigerator, a tray removably disposed in said refrigerator, means in said tray providing a passageway for fluid to the contents of said tray, a refrigerator compressor, and flexible means responsive to the changes in pressure in the crank-case of said compressor for forcing fluid through said passageway into the contents of said tray.

5. In a refrigerator, a tray removably disposed in said refrigerator, a resiliently supported refrigerating unit, and pump means operated by the vibration of said refrigerating unit for forcing fluid into the contents of said tray.

6. In a refrigerator, a tray removably disposed in said refrigerator, a resiliently mounted refrigerating unit, a diaphragm pump operated by the vibration of said unit for forcing fluid into the contents of said tray.

7. A tray for a refrigerator, comprising bottom and side walls, means disposed in said tray and having portions spaced from said bottom wall and from one of said side walls to provide a passageway for fluid, means defining openings for discharging the fluid from said passageway into the contents of said tray, and connection means

- communicating with said passageway and adapted to be connected with a source of said fluid.
8. In a refrigerator, a tray removably disposed in said refrigerator, means for forcing fluid into the contents of said tray to agitate said contents, and control means responsive to the temperature of said contents for operating said fluid forcing means.
9. Ice making apparatus for domestic refrigerating systems comprising a tray, a liner element mounted within said tray to form a sealed compartment with one wall thereof, a plurality of upstanding channels in said liner cooperating with said tray to form passageways communicating with said compartment, a grid within said tray forming a plurality of freezing chambers, and openings in said passageways communicating each of said chambers with one of said passageways.
10. Ice making apparatus comprising a tray, a grid within said tray to provide a plurality of ice moulds, a liner element mounted within said tray to provide an air chamber, means communicating each of the ice moulds formed by said grid with said air chamber, means to refrigerate said tray, and means for supplying air under pressure to said chamber.
11. A liner element for domestic ice trays comprising a wall element having a flange on one end thereof adapted to cooperate with an upstanding wall of said tray to define a sealed air chamber therewith, a foot plate on said liner element having a plurality of passageways therein adapted to rest on the bottom of a tray and to communicate with the air chamber, and a plurality of upwardly facing openings in each of said passageways.
12. Refrigerating apparatus comprising a cooling unit, a power operated cooling medium supply unit operatively connected to said cooling unit, an ice tray mounted in said cooling unit, and means operated by unbalanced forces produced in the operation of said power operated unit for agitating the contents of said tray to remove occluded gases therefrom.
13. Refrigerating apparatus comprising a cooling unit, a power operated cooling medium supply unit operatively connected to said cooling
- unit, an ice tray mounted in said cooling unit, means for agitating the contents of said tray, means for controlling said cooling unit in response to refrigerating demand, said agitating means being connected to be energized and de-energized by said control means, and means responsive to the thermal condition of said tray for allowing or preventing energization of said agitating means by said control means.
14. In a refrigerator, a freezing chamber, a tray removably disposed in said chamber, means in said tray providing a passageway for fluid to the contents of said tray, means in said chamber connected with a source of said fluid, and two part connection means having complementary engageable surfaces for connecting said tray passageway with said means communicating with said source of fluid, and tray guiding means on a side wall of said chamber for insuring alignment and operative engagement between the elements of said two part connector.
15. Refrigerating apparatus comprising a cooling unit, a container in heat transfer relationship with said cooling unit, means for forcing air through the contents of said container, and means responsive to the condition of the contents of said container for regulating the operation of said air-forcing means.
16. Ice making apparatus for domestic refrigerating systems comprising a tray, a removable grid within said tray forming a plurality of ice freezing chambers, and means cooperating with a wall of said tray for forming an air duct therewith, means providing communication between said duct and said freezing chambers, and means for supplying air under pressure to said duct.
17. Ice making apparatus for domestic refrigerating systems comprising a tray, a removable grid within said tray forming a plurality of ice freezing chambers, a liner plate cooperating with a wall of said tray to form an air space, means providing for communication between said air space and each of said freezing chambers, and means for supplying agitating air to said air space under sufficient pressure to cause the air to bubble through water being frozen in said freezing chambers.

ALFRED G. GROSS.
